UNITED STATES PATENT OFFICE.

EDWARD J. SCHREMP, OF ROCHESTER, NEW YORK.

GARMENT-FOLDING TRAY.

Application filed August 8, 1923. Serial No. 656,333.

This invention relates to garment pressing machinery, and more particularly to a garment folding tray useful in supporting a garment to be first pressed in open position, 5 thereafter folded, and finally pressed in folded condition ready to be boxed.

The object of the invention is to provide an improved means of folding and pressing knit goods garments such as underwear and 10 the like in knitting mills to speed up the handling operations whereby the manufacturing cost is reduced simultaneously with the improvement in the appearance of the merchandise.

15 In the manufacture of knit goods, the pieces are usually pressed and then folded by hand to a bundle reduced in size equal to the box in which the garments are to be packed for shipment and sale. Considerable waste of time is involved in manually 20 handling garments and especially in folding the garments. By using my improved garment folding tray, the time ordinarily consumed in handling and folding the garment 25 is reduced, and the garment is more rapidly made ready for packing in the box.

The accompanying drawings show one preferred embodiment of the invention, it being understood how the construction and 30 use of the tray may be altered to better meet the varying conditions of manufacture and use.

Figure 1 illustrates a plan view of the plate like folding tray or garment receptacle 35 with a full length knit garment spread out thereon ready for the first pressing operation.

Figure 2 shows a perspective view of the folding tray in partly folded position with 40 one flap or plate thereof thrown partly over to double the garment back upon itself for the first folding operation.

Figure 3 shows a sectional view taken on the line 3—3 of Figure 1, and illustrates the 45 plate structure of the tray with a pressing pad made as a cover therefor and with a garment placed thereon.

Figures 4, 5, 6, and 7 are diagrams to illustrate the various stages of the folding operation, from the position, in Figure 4, where the garment is first folded transversely in the middle thereof to the place, Figure 7, the garment is reduced to box size with the front and button side placed up.

In the practice of my invention, the garment is first pressed while open full length, and thereafter again pressed after being completely folded. The garment folding tray essentially comprises a plurality of pivoted flaps; and a central stationary body section or press-plate 10 has hinged at one end thereof a half-length folder plate 11. An end folder plate 12 is pivoted on the other end of the said central plate 10; and hinges 13 are employed in pivoting the end plates 11 and 12 upon central plate 10.

A side folder plate or flap 15 is carried upon hinges 16 upon each side of the central plate 10. The hinged flap sections operate independently in order that the folding tray 70 may first start its folding operation from the end plate 11 and thereafter follow up the other folding operations by manipulating the other flaps, one at a time.

Preferably, a pad 18 is secured across the upper face of the folding board or tray, and thus the garment is carried upon a padded pressing surface. The pad 18 is cut at 19 from the outer edge to the axis of the hinge 16 thereby enabling the two side plates 15 to 75 hinge over towards the central plate 10.

The garment is spread upon the press board or tray as shown in Figure 1 with the central portion of the garment disposed over the central plate 10 and with the garment 80 arms supported on the side flaps 15. This arrangement of the garment places the legs thereof across the half-folder flap 11.

The operators thus may quickly spread a knit garment across the press board and 85 promptly run the press board and garment through a full size press whereby the open garment is pressed upon the board or tray in spread open position; and thereafter, the said press board or receptacle still holding the garment is dispatched through folders, either mechanically or manually operated, which promptly starts the operation 90 of the tray flaps in predetermined sequence to carry out the folding operations as shown 100 in the diagrams on sheet 2. In other words, the lengthwise folder flap 11 is first thrust back to double the garment once upon itself. Thereafter quickly follows the operation of one side plate as shown in Figure 5, then 105 the other side plate as shown in Figure 6; and finally the end folder plate 12 completes the folding operation by doubling the al-

ready folded garment back upon itself thus exposing the front and button side of the garment up as shown in Figure 7.

The garment having been folded up to a substantially small bundle or box size, as shown in Figure 7, is now pressed for the second time by dispatching the said pressing tray or board through another pressing machine usually of reduced size; and it is to be understood how a steam heated and steam spray press may be used to soften the garment, raise the nap and provide a lofty appearance, as well as impart a sheen or luster and dry the garment after which the merchandise is removed from the tray and placed in a box for packing and shipping purposes.

Figure 7 shows the garment press folding tray having guide size lines or indications 46, 44, 42, and so on including a plurality of size and guide marks printed upon the pad of the tray functioning as guide lines by which the operators manually position and place the garment upon the tray. For example, a large garment of a size 46 is placed with the shoulder and leg extremities upon the guide lines 46, and a 42 garment would be similarly placed on the lines 42. This arrangement enables garments of different sizes to be quickly placed so that they properly center over the central plate 10.

The use of this tray is more particularly designed for continuous and automatic mechanical handling operations as for example, the said tray is intended to be carried by a conveyer throughout its folding and pressing stages. The tray preferably travels through mechanical folding arms which reduces the garment to box size by automatically closing and opening the flaps constituting the combined press board and tray. It is not always necessary to close the tray flap all the way down for once it is started and passes beyond the vertical the garment itself folds over and

completes the operation, and thus the flaps necessarily move through a limited arc in operation.

What I claim is:

1. A folder comprising a central plate section of suitable size substantially equal to the size of a box or carton in which a folded garment is to be packed, a long flap hinged to one end of the central plate; a short flap hinged to the other end of the plate, and side flaps hinged to the plate. 55

2. A folder comprising a central plate section of suitable size substantially equal to the size of a box or carton in which a folded garment is to be packed, a long flap hinged to one end of the central plate, a short flap hinged to the other end of the plate, side flaps hinged to the plate, a pad disposed over the several hinged flaps to cover the folder and to cover the hinges to provide a padded pressing surface and said pad adapted to flex and fold along the axis of the aforesaid hinges during the operation of the folder. 60 65

3. A combination garment pressing and folding tray comprising, a stationary press plate substantially equal in size to that of a box into which a garment is to be packed, a half-length folder flap somewhat longer and broader than the stationary press plate and being hinged to said press plate to double a garment back upon itself to fold it near the center, a side flap folder plate somewhat longer than the stationary press plate pivoted on each side of the press plate with the flap plate ends projecting beyond the stationary plate, and an end folder plate about equal in size to the stationary press plate and hinged to the press plate between the projecting ends of the aforesaid side flaps. 70 75 80

In testimony whereof I affix my signature this 4th day of August 1923; in the city of Rochester, county of Monroe, and State of New York. 85

EDWARD J. SCHREMP.
